UNITED STATES PATENT OFFICE.

EDGAR M. PERRY, OF BAY, ARKANSAS, ASSIGNEE OF ONE-FOURTH TO C. S. DE FIELD,
OF EAST PRAIRIE, MISSOURI.

REVERSING-VALVE FOR INTERNAL-COMBUSTION ENGINES.

1,248,393.

Specification of Letters Patent. Patented Nov. 27, 1917.

Application filed April 7, 1917. Serial No. 160,477.

To all whom it may concern:

Be it known that I, EDGAR M. PERRY, a citizen of the United States, residing at Bay, in the county of Craighead and State of Arkansas, have invented certain new and useful Improvements in Reversing-Valves for Internal-Combustion Engines; and I do hereby declare the following to be a full, clear, and exact description of the invention, 10 such as will enable others skilled in the art to which it appertains to make and use the same.

This invention relates to certain new and useful improvements in valve mechanisms, 15 and contemplates more especially an improved form of reversing valve for use in connection with internal combustion engines.

An object of the present invention is the production of a valve mechanism including 20 in combination a plurality of ported sleeves adapted to register at certain times for operating the engine in one direction and arranged to register at other times for operating the engine in the opposite direction.

Another object of this invention is to produce a valve mechanism located adjacent the upper end of an engine cylinder, said mechanism comprising a revoluble, conical shaped valve, a coöperating conical shaped 25 reversing sleeve, and an internally ported valve casing communicating with the cylinder of an engine.

Another object of the present invention is the production of a rotary valve mechanism 30 designed to facilitate its easy rotation and possessing certain structural advantages whereby the said valve mechanism is kept cool and all tendencies of the valve to stick or jam are obviated.

A further object of the invention is the production of a simple, efficient and durable valve mechanism which can be readily set for reversing the direction of rotation of 35 the engine.

With these and other objects in view, the invention further consists in the combination and arrangement of the several parts hereinafter to be described and pointed out in the appended claims.

In the accompanying drawings which show by way of illustration an embodiment of my invention,

Figure 1 is a sectional elevation, indicated on the line 1-1 of Fig. 2, of an internal

combustion engine with my improved valve mechanism applied thereto.

Fig. 2 is a plan view.

Fig. 3 is a horizontal sectional view on an enlarged scale on the line 3-3 of Fig. 1, showing the position of the valve when the 60 ports are set to admit a charge of fuel to the engine cylinder.

Fig. 4 is a similar view on the line 4-4 of the valve in the same position as that of Fig. 3.

Fig. 5 is an enlarged vertical sectional view showing the position of the valve when set for exhausting the burnt gases from the cylinder.

Fig. 6 is a horizontal sectional view on the line 6-6 of Fig. 5 showing the path of the burnt gases as discharged from the cylinder.

Fig. 7 is a detailed top plan view of the reversing sleeve lever moved in the direction 75 of the arrow to a position for reversing the direction of rotation of the engine.

Fig. 8 is an enlarged horizontal, sectional view of the valve in the reverse position taken on a line corresponding to that of line 80 4-4 in Fig. 1, said valve being in a position to admit a charge of fuel to the cylinder.

Fig. 9 is a similar view of the valve in the reverse position taken on a line corresponding to the line 3-3 of Fig. 1, said 85 valve being in a position to admit a charge of fuel to the engine cylinder.

Fig. 10 is a similar view of the valve in the reverse position taken on a line corresponding to the line 6-6 of Fig. 5, said 90 valve being shown in a position when the burnt gases are exhausted from the cylinder.

Fig. 11 is a diagrammatic illustration of the interior ported valve casing, showing the 95 ports in said casing in their relative position to those ports provided in the reversing sleeve and the rotating valve.

Fig. 12 is a detached perspective view of the reversing sleeve operable within the 100 valve casing, and

Fig. 13 is a detached perspective view of the rotating valve, the ports of which register with those of the reversing sleeve and the ported valve casing.

This invention has been designed for use in connection with internal combustion engines to facilitate the ready admission of

65

85

105

the fuel and exhaust of the burnt gases through a rotary form of valve. It comprises among other things a conical shaped valve casing located near the upper end of 5 an engine cylinder, a conical shaped reversing sleeve adapted to fit within the said casing and to be set for the direction of rotation of the engine which may be desired, a conical shaped rotatable valve operable with 10 in the conical shaped reversing sleeve, and means including driving gears for rotating the said valve in timed relation to the reciprocation of the piston in the engine. These several conical shaped members are 15 each provided with registering ports to effect the admission and discharge of the fuel as will be hereinafter described. While I have shown my improved form of valve mechanism applied to a single cylinder engine, it will be readily understood that it is 20 equally applicable for use in distributing fuel and effecting the exhaust thereof to a multiplicity of cylinders such as the two, four, six and any of the multiple cylinder 25 types.

Referring to the drawings, in which corresponding reference characters indicate similar parts, the form of internal combustion engine shown comprises a cylinder 1, in 30 which reciprocates the piston 2 operated through the crank shaft 3 suitably journaled in the frame of the engine. The form of engine herein shown is of a conventional type and a further description thereof together with its usual spark plug and other 35 parts will not be given. The improved valve mechanism is mounted within the valve casing 4 which may be formed integral with the engine cylinder or bolted thereto as may be desired. A suitable plate 40 5, together with a spring 6, positions the valve mechanism within the casing against a suitable bearing, as shown. The valve casing is preferably water jacketed as 45 shown, that is to say, it may be in communication with the water jacket surrounding the cylinder of the engine, or it may be jacketed independent thereof.

The reversing valve 7 is of frusto-conical 50 shape corresponding to the bore of the valve casing and is in the nature of a sleeve having a reduced upper end 8 extending through the upper wall of the valve casing, and having secured to it a suitable lever 9 carrying 55 a spring pawl 9^a adapted to coact with a serrated surface 10 for holding the said reversing valve in a set position.

The rotating valve 11 is of frusto-conical 60 shape and fits within the reversing sleeve 7 as shown. This valve is provided with an upwardly protruding shaft 12 which extends through the sleeve portion 8 of the reversing valve. Keyed to the upper end of the shaft 12 is a gear 13 adapted to mesh 65 with a similar gear 14 keyed to a shaft 15,

which latter is mounted in suitable bearings 16 and receives motion through the beveled gears 17 secured to its lower end and adapted to mesh with a beveled gear 18 secured to the crank shaft of the engine. This gear- 70 ing is in timed relation to the cycle of the engine and the corresponding rotation of the valve, and as shown herein is designed to effect one revolution of the rotating valve to two revolutions of the crank shaft of the 75 engine.

Referring to Figs. 11, 12 and 18, the respective ports shown therein will now be described, and the relative registering coöperation thereof in the inlet and exhaust and 80 reversed positions as illustrated in the several horizontal sectional views will be described later. As shown in Fig. 11 (diagrammatically), the valve casing 4 is internally ported as follows: The intake port 20 85 is adapted to receive a charge from an intake manifold I from any suitable source of supply and emit the said charge after passing through the valve into the port 21 and thence into the cylinder of the engine. 90 The exhaust port 22 is designed to receive the burnt gases from the cylinder and emit the same through the exhaust port 23 to one branch E¹ of the exhaust manifold E. The inlet port 24 is used to receive a charge from the inlet port 20 and emit it to the cylinder of the engine when the valve mechanism is reversed and the valve rotated in the direction of the arrow shown in Figs. 8 to 10, 95 inclusive. The exhaust port 26 in the valve casing receives the burnt gases and discharges them through the exhaust port 25 into the branch E² of the exhaust manifold, 100 when the valve is reversed.

When the reversing valve or sleeve 7 is 105 in the position shown in Figs. 1 to 6, inclusive, the ports therein register with the ports in the valve casing as follows: The inlet port 27 in the reversing sleeve registers with the inlet port 34 in the valve 11, 110 port 20 in the valve casing and the inlet port 28 in the reversing sleeve registers with the inlet port 21 of the valve casing for conducting a charge to the cylinder, as will be presently described. The exhaust port 29 115 in the reversing sleeve registers with the exhaust port 22 in the valve casing, and the exhaust port 30 in the reversing valve registers with the exhaust port 23 in the valve casing. When the valve sleeve 7 is reversed as shown in Figs. 7 to 10, inclusive, the intake port 31 of the reversing sleeve will register with the intake port 20 of the valve casing, and the intake port 28 of the reversing sleeve will register with the intake port 24 of the valve casing. The exhaust port 32 in the reversing sleeve will register with the exhaust port 25 in the valve casing, and the exhaust port 33 in the reversing sleeve 120 will register with the exhaust port 26 in the 125 valve casing. The exhaust port 34 in the valve casing will register with the exhaust port 26 in the 130 valve casing.

valve casing leading to the exhaust manifold.

The rotating valve 11 which continuously revolves in the direction of the arrow shown in Figs. 1 to 6 when the engine is rotating in one direction, and which continuously rotates in the direction of the arrow shown in Figs. 8 to 10, when the valve is reversed, and the engine rotated in the opposite direction, is of novel construction and ported as follows: The intake port 34' of the valve 11 registers with the intake ports 27 and 20 of the hereinbefore described reversing sleeve and valve casing, respectively, and directs a charge through said ports into the conduit 35, and thence through the inlet port 36 of the valve 11, which registers with inlet ports 28 and 21 of the reversing sleeve and valve casing, respectively. The exhaust port 37 in the valve 11 is brought into register with the ports 29 and 22 of the reversing sleeve and valve casing, respectively, and permits of a discharge of the burnt gases from the cylinder into the chamber 38 of the valve, surrounding the conduit 35, and thence through the exhaust port 39 in the valve which registers with the exhaust ports 30 and 23 formed in the reversing sleeve and valve casing, respectively.

As shown, the chamber 38 of the valve is closed by an upper wall 40 and a lower wall 41, which allows the burnt gases to pass around the conduit 35. A bottom wall 42 is provided in the valve and forms an inlet chamber 43 communicating with the conduit 35 as shown. An upper inlet chamber 44 is provided in the valve with which the conduit 35 communicates. It will be seen that as the fuel or mixture is admitted, its passage into the chamber 44 through the conduit 35, into the chamber 38 and thence into the cylinder produces a somewhat protracted and cooling effect upon the valve, thereby counteracting the tendency to overheat the valve by the outward passage of the burnt gases. This, together with the cooling effect of the circulating water in the valve casing will prevent the valve from overheating, jamming or sticking as is frequently now the case in rotary types of valves.

Referring to Figs. 1, 3 and 4, wherein the valve and associated parts are shown in the position to admit a charge of fuel to the engine cylinder, and the said valve being operated in a direction of the arrow indicated in said figures, it will be noted that the inlet ports hereinbefore described in connection with the showing in Figs. 11, 12 and 13, are positioned to accomplish this admission of the fuel as will now be described.

In Figs. 1, 2 and 3 of the drawing it will be noted that the charge is admitted through the port 20 in the valve casing and through the registering ports 27 of the reversing sleeve and 34 of the valve into the chamber

44. The charge is then conducted downwardly through the conduit 35 into the chamber 43 and emitted through the registering ports 36 in the valve 28 in the reversing sleeve and 21 in the valve casing, thence to the cylinder of the engine. The charge being drawn into the cylinder of the engine is compressed and ignited in the usual manner to operate the engine. To exhaust the burnt gases from the cylinder, reference will be had to the position of the valve in Figs. 5 and 6. It will be noted that the burnt gases are exhausted through the registering ports 22 in the valve casing, 29 in the reversing valve and 37 in the valve, thence through the chamber 38 surrounding the conduit 35 and out through the registering ports 39 in the valve 30, in the reversing sleeve and 23 in the valve casing.

When the engine is reversed by manipulating the lever 9 to the position shown in Fig. 7 of the drawing, the inlet and exhaust ports, as shown in Figs. 8, 9 and 10 are brought into register for operating the engine in an opposite direction. The position of the valve in Figs. 8 and 9 shows a charge being admitted to the engine cylinder. It will be noted in Fig. 9 that the ports 20 in the valve casing, 31 in the reversing sleeve and 34' in the valve register. The charge passes through the chamber 44 into the conduit 35, thence into the chamber 43 and is emitted through the registering ports 36 in the valve, 28 in the reversing sleeve and 24 in the valve casing into the cylinder (see Fig. 8). In this position the charge is drawn into the cylinder and ignited in the usual manner. The exhaust gases are connected through the valve as it rotates to the position shown in Fig. 10 of the drawing, that is to say, the exhaust gases are conducted through the ports 26 in the valve casing, 33 in the reversing sleeve and 37 in the valve, into the chamber 38, thence through the ports 39 in the valve, 32 in the reversing sleeve, 25 in the valve casing, thence into the exhaust manifold.

It will be seen from the foregoing description that the operation of the engine in opposite directions is controlled by the manipulation of the reversing sleeve or valve 7 by moving the lever 9 in the respective positions shown in Figs. 2 and 7. It will also be obvious that the relative positioning of the frusto-conical valve reversing sleeve and correspondingly formed valve casing, together with the chambered construction of the rotary valve for conducting the fuel to the cylinder and effecting the exhaust therefrom, produces an efficient, durable and economical means for controlling the operation of an internal combustion engine. Various changes in the form and construction of my improved valve may be resorted to within the scope of my invention.

set out in the claims, and I do not limit myself to the exact proportions and details of construction herein set forth.

Having thus described my invention, what I claim and desire to secure by Letters Patent is:

1. In an internal combustion engine, the combination with a ported cylinder having a piston therein and a valve casing, of a rotary valve mounted in said casing having a fuel inlet conduit therethrough and an exhaust chamber surrounding said inlet conduit, a plurality of inlet ports in said valve communicating with the inlet conduit, another port in said valve communicating with the opposite end of the inlet conduit and one of the ports in the cylinder, a plurality of exhaust ports in said valve communicating with the aforesaid exhaust chamber and a reversing valve interposed between the valve casing and rotary valve, said reversing valve having a plurality of inlet and exhaust ports adapted to establish communication between the ported cylinder and the rotary valve for operating the engine in opposite directions.

2. In an internal combustion engine, the combination with a ported cylinder having a piston therein and a valve casing, of a rotary valve mounted in said casing having a fuel inlet conduit therethrough, inlet chambers communicating with said conduit at each end thereof, an exhaust chamber surrounding said conduit and interposed between the aforesaid inlet chambers, a plurality of inlet ports in said rotary valve communicating with one of the inlet chambers, another port in said rotary valve communicating with the other inlet chamber and one of the ports in the cylinder, a plurality of exhaust ports in said valve communicating with the aforesaid exhaust chamber, and a reversing valve interposed between the rotary valve and valve casing having ports adapted to register with the aforesaid inlet and exhaust ports, and ports of the cylinder for operating the engine in the desired direction of rotation.

3. In an internal combustion engine the combination with a ported cylinder having a piston therein and a valve casing, of a rotary valve mounted in said casing having a fuel inlet conduit therethrough and an exhaust chamber surrounding said inlet conduit, a plurality of inlet ports in said valve communicating with the inlet conduit, another port in said valve communicating with the opposite end of the inlet conduit and

with one of the ports in the cylinder, a plurality of exhaust ports in said valve communicating with the aforesaid exhaust chamber, a reversing valve interposed between the valve casing and rotary valve, said reversing valve having a plurality of inlets and exhaust ports therein adapted to establish communication between the ported cylinder and the rotary valve for operating the engine in opposite direction, and means including a spring and opposed bearing for positioning the rotary valve and reversing valve snugly against the walls of the valve casing.

4. In an internal combustion engine the combination with a ported cylinder having a piston therein and a valve casing, of a rotary valve mounted in said casing having a fuel inlet conduit therethrough, inlet chambers communicating with said conduit at each end thereof, an exhaust chamber surrounding said conduit and interposed between the aforesaid inlet chambers, a plurality of inlet ports in said rotary valve communicating with one of the inlet chambers, another port in said rotary valve communicating with the other inlet chamber and one of the ports in the cylinder, and a plurality of exhaust ports in said valve communicating with the aforesaid exhaust chamber.

5. In an internal combustion engine, the combination with a frusto-conical valve casing, of a rotary frusto-conical valve mounted in said casing having a fuel inlet conduit therethrough and an exhaust chamber surrounding said inlet conduit, a plurality of inlet ports in said valve communicating with the inlet conduit, another port in said valve communicating with the opposite end of the inlet conduit and one of the ports in the cylinder, a plurality of exhaust ports in said valve communicating with the aforesaid exhaust chamber, a reversing valve interposed between the valve casing and rotary valve, said reversing valve having a plurality of inlet and exhaust ports adapted to establish communication between the ported cylinder and the rotary valve for operating the engine in opposite directions, and means including a manually controlled lever for operating the reversing valve.

In testimony whereof I affix my signature in presence of two subscribing witnesses.
